UNITED STATES PATENT OFFICE.

WILLIAM E. PEMBLETON, OF WITTENBERG, WISCONSIN.

TELEPHONY.

SPECIFICATION forming part of Letters Patent No. 726,984, dated May 5, 1903.

Application filed June 19, 1901. Serial No. 65,095. (No model.)

To all whom it may concern:

Be it known that I, WILLIAM E. PEMBLETON, a citizen of the United States, and a resident of Wittenberg, in the county of Shawano 5 and State of Wisconsin, have invented certain new and useful Improvements in Telephony; and I do hereby declare that the following is a full, clear, and exact description thereof.

My invention has for its object to provide 10 for secrecy in the matter of communication by telephone on party-lines, whether local or long distance, as well as to prevent switchboard operators from hearing conversation carried on through private-line telephones 15 without knowledge of those conversing, said invention consisting in what is hereinafter particularly set forth with reference to the accompanying drawings and subsequently claimed.

20 Figure 1 of the drawings is a diagram illustrating my improved telephone apparatus at a subscriber's station on a party-line; Fig. 2, a diagram illustrating means for connecting a party-line and switchboard; Fig. 3, a diagram 25 illustrating a switchboard operator's signaling and talking set.

Referring by letter to the drawings, A B indicate parallel conductors constituting the line of an electric-telephone system in which 30 my improvements are embodied, particular reference being had to a party-line that may be either local or long distance. The party-line subscriber telephone illustrated in Fig. 1 has its tilt-hook lever C in connection with 35 a pull-spring E, that expands under the weight of receiver D when the same is hung on the lever, the telephone being then disconnected from the line. The lever is shown provided with an upper arm b, that serves as 40 a circuit-closer between spring-contacts c d when the receiver D is taken off hook and said lever permitted to rise by contraction of the spring E in connection therewith. The contact c is electrically connected to conductor A, and contact d is normally in touch with 45 a contact-point e, electrically connected to a magneto F or other current-generator in circuit with an electric signal G, (audible or otherwise,) the primary of an induction-coil 50 H, and conductor B, the secondary of this coil and a resistance I in series therewith being permanently bridged between said con-

ductors. Lever C is also shown provided with a depending finger f, that in its normal position prevents a spring-contact g from being moved into touch with a contact-point h, that is electrically connected to conductor A and a battery J, the spring-contact being likewise connected to said battery, that of itself is in circuit with local battery K, transmitter L, and induction-coil M of the telephone.

Contact d is electrically connected to an electromagnet N, likewise connected to conductor B and the primary of an induction-coil H, the armature of the magnet being a lever O, electrically connected to a resistance I, likewise connected to the secondary of said induction-coil. Resistance I is also electrically connected to the primary of induction-coil M and a contact i under an extremity of the aforesaid tilt-hook lever parallel to other contacts i' i''. Contact i' is in electric connection with the secondary of induction-coil M, and contact i'' has like connection with the aforesaid batteries. A spring-contact j is shown fast to the other extremity of lever O, opposed by a contact-point k, with which it is normally out of touch, this point being electrically connected to the secondary of induction-coil H and an electromagnet P, this magnet being likewise connected to the two batteries aforesaid. The armature of the electromagnet P is part of one arm of a bell-crank lever Q, and the other arm of this lever is made to constitute a catch 85 for the tilt-hook lever C, above specified. To limit play of levers C, O, and Q, stop-screws 90 are conveniently arranged as herein shown, and a spring-contact n is arranged in electric connection with conductor A to be put in touch with contact d at will.

When the telephone-receiver D is taken off hook and lever C automatically tilted to have its arm b close the circuit in which contacts c d are placed, the contact d is lifted clear of contact-point e, with which it is normally in touch. If the line is then in use, current therefrom will flow from conductor B through electromagnet N, contact d, lever-arm b, and contact c to conductor A, the armature of said magnet being then attracted to thereby tilt lever O, and thus bring contact j in touch with point k to close the circuit that includes electromagnet P, battery K, transmitter L,

and primary of induction-coil M, the armature of electromagnet P being attracted to tilt bell-crank lever Q and bring catch-arm of same under the adjacent end of the tilt-hook lever, thereby preventing the same from coming into touch with the contacts i i' i'', the receiver of the telephone being thus cut out from the line to prevent overhearing. To ascertain if the line is busy without taking receiver D off hook, the contact n may be put in touch with contact d to close circuit with the line by way of electromagnet N, and if the armature of said magnet be attracted it is evident that said line is in use. 15 If there be no current on the line when receiver D is taken off hook, the spring E will tilt lever C far enough to have its arm b clear the contacts c d, its finger f being at the same time carried clear of contacts g h and one 20 end of said lever brought into touch with contacts i i' i'', thereby closing both primary and secondary circuits of the telephone. Battery J is now in circuit with conductor A, contact i'', lever C, contact i', secondary of 25 induction-coil M, receiver D, and conductor B. Hence as there is current on the line none of the other telephones on said line can cut in; but if contact g be put in touch with point h said battery will be short-circuited 30 for the time being to permit the telephone that is called to cut in on the aforesaid line.

The calling is done by operating generator F when contact d is in touch with contact-point e, whereby a closed circuit is established through said generator, signal G, primary of induction-coil H, and electromagnet N, there being induced current through the secondary of said coil and the resistance I, that are bridged between the conductors A 35 B of the line. Magnet N being energized, its armature is attracted and lever O brought into circuit with the secondary of induction-coil H, cutting out the resistance I aforesaid. Calling-current being generated on the line 40 at one telephone, it will flow through resistance I and secondary of induction-coil H of each other telephone on the party-line, inducing current in primary of said coil to thereby energize electromagnet N and attract its armature, the lever O being thus operated to close a circuit, as aforesaid, from which said resistance is eliminated, this resistance at each telephone being at all times 45 as high as possible in proportion to the number of cells of the battery J aforesaid.

To connect party-lines, apparatus similar to that shown in Figs. 2 and 3 is employed at a switchboard-terminal of the lines in connection with the flexible cord of an operator's 50 signaling and talking set, this cord having plug-terminals engageable with jacks of the apparatus. One strand of the cord joins sleeves p, and the other strand joins pins q, that extend through said sleeves beyond the 55 same and are insulated therefrom, these sleeves and pins constituting the preferred form of plug-terminals for said cord. Each

jack preferably consists of a longitudinally-slotted conductor-shell R, a spring-contact r in connection therewith having a bend extending 70 through the slot, and another spring-contact s forward of said shell electrically connected to conductor A, contact r being likewise connected to conductor B and opposed by a contact-point t, electrically connected to another 75 spring-contact u, that closes on a contact-point v, wired with said contact r to conductor B of the line. Contact-point t and contact u are put in circuit with a signal G', primary of an induction-coil H', a generator 80 F', electromagnet N', and conductor A of the line, the secondary of said coil and resistance I' being permanently bridged between both conductors of said line.

The armature of electromagnet N' is part 85 of a lever O', electrically connected to conductor A and another electromagnet P', that is likewise connected to a battery K', this battery being similarly connected to a contact-point w, opposed to said lever. Battery 90 K' is also electrically connected to resistance I', in like connection with the secondary of induction-coil H', similarly connected to conductor B of the line. The armature of magnet P' is one arm of a bell-crank lever Q', the 95 other arm of which is offset to come between shell R and contact s of the jack when said magnet is energized.

If the jack is plugged, the plug-sleeve p, acting on contact r, will force the same into 100 touch with point t, and if there is current on the line the electromagnet N' will attract armature-lever O', and thereby close the circuit containing the other electromagnet P', energization of this magnet operating to tilt armature-lever Q' into position to serve as a barrier that prevents plug-pin q from coming 105 into touch with contact s while said line is busy. To make busy test of the line without plugging the jack, the spring-contact u is put in touch with contact-point v to close the magnet-circuit, and if there be current on 110 said line the armature-levers will be attracted, as above described.

The pin-strand of the flexible connecting- 115 cord is shown in circuit with a pair of contact-blades x, in touch with extremities of a conductor-bar y, and the sleeve-strand of said cord is shown connected to generator F', put in circuit with contact-points z in opposition to said blades, normally out of touch with the same. Spring-contacts b' are also shown arranged to oppose the contact-blades x, normally out of touch with the same, and a 120 L-lever S is arranged to swing between said blades and move either of them into touch with an adjacent spring-contact b' and contact-point z, thus closing a signal-circuit 125 through the aforesaid cord.

The operator's set is shown as including 130 brushes T U, each comprising a series of flexible radially-disposed conductor-strips having insulation-facings, these facings of one series of brush-strips being in a direction opposite

- those of the other series of similar strips. One conductor-strip in each brush is electrically connected to the bar y . Another of these strips in each brush is likewise connected to the secondary of an induction-coil V , put in circuit with the plug-sleeve strand of the flexible cord aforesaid, the primary of this coil being in circuit with a battery W and transmitter X . Another conductor-strip in brush T is electrically connected to an audible electric signal Y , the corresponding strip in brush U being likewise connected to a similar signal Z , having a different tone from the one Y , both of these signals being adjacent to a transmitter X in circuit through the same with a battery W and primary of the induction-coil V aforesaid. A fourth strand b'' of brush U is electrically connected to the spring-contacts b' aforesaid. The brushes are in the path of the operator's lever A' , and swing of this lever in one direction will cause contact of the same with insulation of one brush and the conductor-strips of the other brush, said lever being a circuit-closer in either direction of its throw. A spring-contact c' , also in the path of lever A' in one direction of its swing, is electrically connected to the secondary of an induction-coil B' and the flexible cord, the primary of the coil being in circuit with the transmitter L' and local battery K'' of the operator's telephone, the receiver D' of this telephone and a battery J' being electrically connected to said cord and a contact-point d' opposed to said spring-contact normally out of touch with same. By means of push-button mechanism shown at C' the battery J' may be short-circuited from the line to unlock the telephone of the called subscriber thereon, so that the one called may be cut in.
- When lever A' is swung from the position shown, it will touch on insulation of brush U and the conductor-strips of brush-strips of brush T before it operates to force contact c' into touch with point d' , and thus signal Y will be energized to notify subscribers that the operator's telephone has been cut in. Reverse motion of the operator's lever will close circuit with brush U to energize signal Z , and thus notify subscribers in communication that the operator's telephone is cut out.
- The strip b'' in brush U , wired to contacts b' , prevents operator from opening one side of the plug-cord circuit with lever S and then cutting in without having the cut-in signal transmitted.
- Having thus described my invention, what I claim as new, and desire to secure by Letters Patent, is—
1. In a party-line electric-telephone system, the combination of the spring-controlled tilt-hook lever constituting the receiver-hanger and closer for the normally open primary and secondary circuits of each subscriber's telephone, a catch arranged to be moved in the way of the circuit-closing portion of said lever, electric catch-operating mechanism in
- independent open circuit with the line of said system, and an arm of the aforesaid lever constituting a temporary closer for said independent circuit ahead of the closing of said other circuits; whereby in case of current on the line when the receiver of said telephone is taken off hook the catch will be actuated to prevent closing of the aforesaid primary and secondary circuits. 70
2. In a party-line electric-telephone system, the combination of an automatic current-generator in the primary circuit of each subscriber telephone, means constituting part of said telephone for automatically preventing cut in of same when there is current on the line, and other means for short-circuiting said generator at will subsequent to a cut in of the aforesaid telephone to thereby temporarily divert current from said line to permit the cut in of another telephone called by the one aforesaid. 80
3. In a party-line electric-telephone system, the conductors A , B , and subscribers' telephones each comprising spring-controlled tilt-hook lever C , having upper arm b , spring-contacts c , d in the path of the lever-arm, contact-point e with which contact d is normally in touch, current-generator F electric signal G , induction-coil H resistance I , batteries J , K , transmitter L , induction-coil M , receiver D , electromagnet N , armature O , contact j , point k , electromagnet P , combined armature and catch Q and contacts i , i' , i'' , all arranged and connected as herein set forth. 90
4. In a party-line electric-telephone system, the conductors A , B , and subscribers' telephones each comprising spring-controlled tilt-hook lever C , having upper arm b , spring-contacts c , d , in the path of the lever-arm, contact-point e with which contact d is normally in touch, current-generator F , electric signal G , induction-coil H , resistance I , batteries J , K , transmitter L , induction-coil M , receiver D , electromagnet N , armature O , contact j point k , electromagnet P , combined armature and catch Q , contacts i , i' , i'' , and contact n , all arranged and connected as herein set forth. 95
5. In a party-line electric-telephone system, the conductors A , B , and subscribers' telephones each comprising spring-controlled tilt-hook lever C , having upper arm b , spring-contacts c , d , in the path of the lever-arm, contact-point e with which contact d is normally in touch, current-generator F , electric signal G , induction-coil H , resistance I , batteries J , K , transmitter L , induction-coil M , receiver D , electromagnet N , armature O , contact j , point k , electromagnet P , combined armature and catch Q , and contacts g , h , i , i' , i'' , all arranged and connected as herein set forth. 105
6. In an electric-telephone system, a switch-board-terminal apparatus for independent party-lines comprising jack-shell R , contact r having a bend extending through a shell-slot, contact s , current-generator F' , electric signal G' , induction-coil H' , resistance I' , electromagnet N' , armature O' , contact-point 110
- 120
- 125
- 130

w, battery K', electromagnet P', and armature-lever Q', all arranged and connected as herein set forth, together with an operator's connecting-cord, each plug-terminal of which 5 comprises a sleeve and a pin that being in insulated engagement with the sleeve extends forward of the same.

7. In an electric-telephone system, a switch-board-terminal apparatus for independent 10 party-lines comprising an automatic current-generator in a calling-circuit, means constituting part of each subscriber telephone of said lines for preventing cut in of same when the aforesaid lines are connected and influenced by current from the generator, and other means for short-circuiting said generator at will.

8. In an electric-telephone system, a switch-board-terminal apparatus for independent 20 party-lines comprising an electric signal and contacts u, v, in open-circuit connection with line conductors, and means for energizing the signal when the circuit is closed by said contacts.

25 9. In an electric-telephone system, a switch-board-terminal apparatus including an operator's calling and talking set comprising a pair of radially-disposed brushes the flexible conductor-strips of which have their free 30 ends faced upon one side with insulation, the insulation facings in one brush being in a direction opposite those in the other; a plug-cord and a strip of each brush electrically connected, an induction-coil having its secondary in circuit with said cord and another strip of each brush, an audible electric signal mechanism in circuit with the primary of said coil and a strip of each brush independent of the strips aforesaid, an operator's circuit-35 closing lever arranged to be swung against 40 closing lever arranged to be swung against

said free ends of the brush-strips, and a talking-circuit closer opposed to the lever in one direction of its throw.

10. In an electric-telephone system, a switchboard-terminal apparatus including an operator's calling and talking set comprising a pair of radially-disposed brushes the flexible conductor-strips of which have their free 45 ends faced upon one side with insulation, the insulation facings in one brush being in a direction opposite those in the other, a plug-cord having a strand thereof interrupted by 50 spring-contacts normally in touch with extremes of a conductor electrically connected to one of the strips in each brush, a current-generator wired to contact-points opposed to the spring-contacts out of touch with same, a pivotal 1-lever intermediate of said spring-contacts, another pair of spring-contacts 55 opposing those aforesaid out of touch with same and electrically connected to each other and a strip of one of the brushes, an induction-coil having its secondary in circuit with another strand of said cord and an independent strip of each brush, an audible electric 60 signal mechanism in circuit with the primary of said coil and another independent strip of each brush, an operator's circuit-closing lever arranged to be swung against 65 said free ends of the brush-strips, and a talking-circuit closer opposed to this lever in one direction of its throw.

In testimony that I claim the foregoing I have hereunto set my hand, at Wittenberg, in the county of Shawano and State of Wisconsin, in the presence of two witnesses.

WILLIAM E. PEMBLETON.
